ATTORNEYS

UNITED STATES PATENT OFFICE.

ALBERT P. TREADWELL, OF ATLANTA, GEORGIA, ASSIGNOR OF ONE-HALF TO JOSIAH FLOURNOY, OF COLUMBUS, GEORGIA.

INSECTICIDE CONTAINER AND DISTRIBUTOR.

Application filed September 24, 1924. Serial No. 739,722.

To all whom it may concern:

Be it known that I, ALBERT P. TREADWELL, a citizen of the United States, and a resident of Atlanta, in the county of Fulton and State of Georgia, have invented certain new and useful Improvements in Insecticide Containers and Distributors, of which the following is a specification.

My invention relates to improvements in insecticide containers and distributors of that class to which the device disclosed in United States Patent #1,500,514, granted July 8, 1924, to A. L. Milligan belongs, and it consists in the combinations, constructions and arrangements herein described and claimed.

An object of the present invention is to provide a container and distributor of the character described which has simple, reliable and efficient pneumatic means of novel construction for causing the discharge of finely divided powder from the outlet of the container section of the device without permitting passage of the insecticide from the container section to the space between relatively movable parts of the device.

A further object of the invention is to provide an insecticide container and distributor of the character described which is conveniently and easily operable, compact in form, efficient in use, and thoroughly practical commercially.

Other objects and advantages will be apparent from the following description considered in conjunction with the accompanying drawings, in which:

Figure 1 is a longitudinal vertical section through a practical embodiment of the invention,

Figure 2 is a perspective view of a slightly modified form of the same device,

Figure 3 is a fragmentary vertical section through the discharge end portion of the modification exhibited in Figure 2,

Figure 4 is a section on the line 4-4 of Figure 1,

Figure 5 is a section on the line 5-5 of Figure 1, and

Figure 6 is a relatively enlarged fragmentary perspective view of the intake end portion of a blow tube with which each form of the device is equipped.

Referring now to the drawings, and particularly to Figure 1, it will be observed that

a practical embodiment of the invention includes a container section having a tubular body 1, covered at its forward end by a cap 2 which may be secured on the body 1 in any suitable known manner. The cap 2 carries a nozzle or tubular discharge member 3 which tapers toward its outer end and extends from a discharge opening 4 in the head of the cap. The body 1 is closed at its rearward end by an end member 5. An air displacing section which is comprised in the device includes a body portion 6 which slidably fits on the body 1 and is covered at its rearward end with an end member 7. The length of the body 6 of the air displacing section is slightly greater than the length of the body 1 of the container section from the rearward end of the latter to the inner end of the cap 2, which is indicated by 8, and which serves as a stop for limiting the sliding movement of the body 6 on the container section toward the forward end of the latter. An air space 9 thus will be defined within the air displacing section between the end members 5 and 7 of the two sections of the device, irrespective of the position of the air displacing section on the container section. This air space will be enlarged as the air displacing section is drawn rearwardly on the container section, and of course will be decreased in area as the air displacing section is moved forwardly on the body of the container section.

A blow tube for establishing communication between the air space 9 and the interior of the container section is designated at 10, and has the rearward end portion thereof secured in an opening 11 in the end member 5. The opening 11 is in line with the opening 4 and is located adjacent to the juncture of the end member 5 with the body 1. The tube 10 is connected with the wall of the opening 11 in any suitable known manner so as to be rigid with the end member 5 and to have a fluid-tight fit in the opening 11. The tube 10 extends within the body 1 nearly to the forward end of the latter, but terminates short of the head of the cap 2. The rearward end portion of the tube 10 may protrude into the air space 9 and is reduced at its extremity at 12 so that the inner wall of the reduced portion will serve as a seat for a ball valve 13 which is freely movable in the rearward end por-

- tion of the tube 10. The forward movement of the ball valve 13 in the tube 10 is limited by a plurality of inwardly extending radial stop fingers or lugs 14.
- 6 The end member 7 is provided with an air intake opening 15 which preferably is in line with the openings 11 and 4 and is covered at its inner end by an inwardly opening flap valve 16.
- 10 From the foregoing description of the various parts of the device, the operation thereof may be readily understood. When the air displacing section is moved rearwardly of the container section, the space 9 is enlarged and air is permitted to pass into the space 9 through the opening 15. At the same time, there will be sufficient suction on the space within the tube 10 to move the ball valve 13 to its seat at the rearward end 20 of the tube so that passage of insecticide through the tube from the space within the container section 9 during the movement of the air displacing section on the container section is positively prevented.
- 25 Forward movement of the air displacing section on the container section will reduce the size of the air space 9 and air will be forced at high velocity through the opening at 12 into and through the pipe 10 into 30 the interior of the container section, thus blowing insecticide from the container section through the opening 4 and nozzle or spout 3 in spray formation and at a high velocity.
- 35 The modified form of the device illustrated in Figures 2 and 3 differs from the preferred form of the device only in that the body 1 of the container section is covered at its forward end with a cap 2' having a 40 lateral opening 4' from which a discharge nozzle or spout 3' extends in lieu of the cap 2 which has been hereinbefore described.

The operation of the modified form of the device is identical in essential respects with the operation of the preferred form of the 45 device, and therefore need not be set out herein.

It will be obvious from the foregoing that the end member 5 may be made separate from the body 1 and detachably secured to 50 the latter in any suitable known manner to permit the charging of the container section with a cartridge filled with insecticide if it is so desired, without departing from the spirit and scope of the invention, the tube 55 10 of course being carried by the detachable end 5 and the inner wall of the container section having means for engaging with the cartridge so that an aperture therein when the cartridge is pierced by the tube 10, will 60 be in line with the outlet of the container section.

Other modifications and adaptations of the forms of the device herein disclosed also may be provided without departing from the 65 spirit and scope of the invention, and I therefore consider as my own all such modifications and adaptations thereof as fairly fall within the spirit and scope of the appended claim.

70 I claim:—

An insecticide container and distributor comprising a container section having the forward end portion thereof provided with an outlet, a blow tube extending through the 75 rearward end portion of the container section longitudinally thereto, an air displacing section having a tubular body slidably fitting on said container section and having a closure for the rearward end thereof, and 80 a forwardly opening check valve in the rearward end portion of said tube.

ALBERT P. TREADWELL.
